Printed in October 1930

Laben Eddy of Taunton Mass.
Letters Patent No. 329. Dated Oct. 29. 1850.

The Schedule referred to in these Letters Patent and making part of the same.

To all Persons to whom these Presents shall come:

Be it known that

I Laben Eddy, of Taunton in the County of Bristol, and State of Massachusetts have invented or produced a new and ornamental design for a Cooking Stove, and I do hereby declare that the same is described and represented in the following specification and accompanying drawing letters figures and references thereof.

The said drawing above mentioned exhibits a side elevation of a Cooking Stove, and two vertical sections of the side thereof.

The ornamental composition of the side of the stove independent of those of the doors may be said to be composed of the feet, the base, the cornice and the blockings, all extending in relief from a flat plate or body plate. Each foot is seen at E or F and is composed of two scrolls of leaves extending at right angles or thereabouts from one another, and a common central piece, one of the said scrolls being in the plane of the picture, while the other may be said to stand at right angles to it, and to extend along the under edge of the front or rear end of the stove. Each scroll b, b² of leaves starts from a bead a.

The base is composed of a plain fillet c, a cyma recta d, a broad fillet e, (which is ornamented with a series of sunken inclined parallelogrammatic recesses) a small fillet f, a cyma reversa g, a fillet h, a band or belt i, of diamonds in relief, a fillet k, and a cyma reversa l, the whole having the relief and proportion as exhibited in the drawings.

The blockings, are the two lines or columns of ornaments m, n, which make the finish of the vertical edges of the stove plate G, and which stand in bold relief therefrom. Their arrangement on the ends of the stove is the same as on the sides, except that the members m, m, are made as long on the ends of the stove as the members n, n, are on the sides, while the latter (n. n) are made as short on the ends of the stove

as the members m, m, are on the sides of it. The Cornice is composed of an echinus ovolo or quarter round o. A band or belt of diamond work p. another echinus q, a cyma recta r, a broad band or fillets s, and a coving t. composed of a reversed echinus u. An astragal v, and a cyma reversa w.

The main oven door is seen at H. while the lesser oven and fire place doors are seen at I and K.

The ornamental configuration of the main oven door consists. First, of a centre piece consisting of a circular shield c' (bounded by a bead d') a rosette a', and a concentric row of five leaves b' b' b' & c, the whole being as seen in the drawings. Second, a panel of angular rays or radiations e' bounded by a bead f' and a band of diamond work g' which, in turn is bounded by a border h' the whole being as seen in the drawings.

Each of the small doors has its ornamental configuration composed of an ornament like that on the centre shield of the large door, the said ornament being in relief, on a square shield i', enclosed within a beads l', which is surrounded by a band of diamond work k' which, in its turn, is encompassed by a border m' the whole being as seen in the drawings.

What I claim as my invention, is the ornamental composition of each foot E or F.

I also claim the ornamental composition of either the base, the cornice, or the blockings, as well as a combination of the whole of the same.

I also claim the ornamental composition or design for the main oven door H, as well as that of either of the small doors I or K.

In testimony whereof I have hereto set my signature this twelfth day of August A.D. 1850.

Witnesses.
